WHOLE No. 1,478.

School Desk.

WILLIAM P. UHLINGER, OF PHILADELPHIA, PA.

Letters Patent for a Design No. 113, dated October 8, 1861.

SPECIFICATION.

TO ALL WHOM IT MAY CONCERN:

Be it known, that I, WILLIAM P. UHLINGER, in the city of Philadelphia, and State of Pennsylvania, have invented or produced a new and original design for a School Desk; and I do hereby declare that the following is a full and exact description of the same, reference being had to the accompanying drawing, which forms a part of this specification, and represents a side elevation of two desks, fig. 1 and fig. 2, in their relative positions.

To each desk is attached a seat A, for the next preceding desk; these seats swing on bearings, in such a manner as to be readily elevated to the vertical position represented at fig. 2, thus facilitating the cleaning of the floor, etc., by allowing convenient passage between the desks. Each desk consists of two cast iron frames or uprights B, (of the configuration represented in the drawing,) to the top of which is secured the platen or table C, being in the usual manner slightly inclined towards the occupant. The desk is further provided with a back D, securely attached to the frames B, and slightly projecting above the back of the table C.

I wish it to be understood, that I do not desire to claim the mechanical arrangement of the desk, although I have partly described the same in the specification.

But what I claim, and desire to secure by Letters Patent, is—

The ornamental configuration of the cast iron uprights B, constituting, in combination with a table C, back D, and seat A, a new and original design for a school desk, as above set forth and represented in the annexed drawing.

Witnesses:

C. BRAZER,
STEPHEN ALLBUTT.

W. P. UHLINGER.
